UNITED STATES PATENT OFFICE.

KARL ENGEL, OF ARLINGTON, MASSACHUSETTS, ASSIGNOR TO UNITED SHOE MANUFACTORY COMPANY, OF PATERSON, NEW JERSEY, A CORPORATION OF NEW JERSEY.

METHOD OF MAKING SHOES.

1,246,730.

Specification of Letters Patent. Patented Nov. 13, 1917.

Application filed December 2, 1914. Serial No. 875,126.

To all whom it may concern:

Be it known that I, KARL ENGEL, a citizen of the United States, residing at Arlington, in the county of Middlesex and State of Massachusetts, have invented certain Improvements in Methods of Making Shoes, of which the following description, in connection with the accompanying drawings, is a specification, like reference characters on the drawings indicating like parts in the several figures.

This invention relates to methods of making shoes and particularly to a novel method of making welt shoes. In general the invention aims to produce a serviceable and neat appearing shoe which can be manufactured at a low cost and not only with comparatively unskilled labor but also with less labor than is ordinarily required to produce a shoe of the same grade. More particularly the invention aims to construct a shoe which has the principal advantages of the well known "Goodyear welt shoe" and in addition is possessed of greater flexibility than said Goodyear shoe.

The invention in its various aspects will now be more particularly described in connection with the accompanying drawings which illustrate the different steps, and will 30 then be pointed out in the claims.

Figure 1 is a perspective view of an insole made in accordance with this invention;

Fig. 2 is a perspective view of a last upon which the shoe may conveniently be made; 35 and

Fig. 3 is a perspective view, partly in section, showing the prepared upper in lasted position on the last and ready to receive the outsole.

40 In carrying out the novel process of the invention a shoe upper 2 is first cut out substantially to its final outlines or to such size that the lower edge of the upper along the shank and at the forepart will terminate substantially at the last edge, thereby saving the upper leather ordinarily provided to attach the upper to the insole and which is trimmed off in later operations. The toe and heel portions of this upper together with the toe 45 and heel stiffeners are then molded, preferably by the processes described respectively in my United States Letters Patent Nos. 947,895 and 1,001,745, to the shapes which these parts assume in the finished shoe. In order to provide sufficient material to enable the

upper 2 to be tensioned and lasted over upon the insole and also for securing it to an insole, a narrow strip of strong canvas 3 is attached to the lower edge of the molded upper through the shank and about the forepart or in a lined shoe the lining may be extended beyond the lower edge of the upper and secured to its marginal portion. This canvas strip 3 as herein shown is secured by stitches 5 to the inner face of the molded upper 2 along its lower edge so that it projects a considerable distance beyond said edge, a welt 6 is also secured, preferably by the same stitches 5, along the lower edge of the molded upper 2 upon the outside thereof. The welt 70 6 extends through the shank and about the forepart of the upper and is secured along its inner edge so as to project outwardly.

The insole to which the molded upper 2 is secured is made in two parts so that a fastening clenching plate may be located between these parts to clench the upper securing fastenings which pass through one part of the insole, whereby these clenched fastenings may be covered in the shank and 80 forepart of the finished shoe by the other part of the insole and thus provide a smooth interior for the shoe. To this end the illustrated insole comprises preferably an upper flap 8 of canvas or similar material to which the upper is secured, and a lower flap 9 of leather attached to the main sole only at the toe end thereof by cement or other suitable means and terminating approximately at the forward edge of the heel seat, although an insole of leather split from the forward edge of the heel seat toward the toe thereof and terminating short of the toe end or an insole 90 of other suitable material may also be employed.

95 It has been found advantageous to provide the last 12 upon which the shoe is made with a clenching plate for the purposes above pointed out and to this end a sheet metal plate 13, shaped to the contour of the bottom face of the last and terminating short of the toe end thereof, is secured to the bottom of the last, at the heel portion only, by the rivets 16. The portion of the bottom face of the last extending beyond the forward edge 100 of the plate is provided with an additional plate 18 secured directly to the bottom of the last by the rivets 19.

105 The novel last disclosed herein as used in practising the process of the present invention.

tion is not claimed herein, but is claimed in my application Ser. No. 196,360, filed Oct. 18, 1917, which is a division of the present application.

- 5 The insole is placed upon the last with the lower flap 9 interposed between the unattached portion of the plate 13 and the bottom face of the last 12 and with the upper flap 8 covering the entire bottom face of the last. 10 The prepared upper is then assembled on the last and lasted over on to the insole 8, 9 with the aid of the lasting strip 3 and the marginal edge of the upper at the heel and the extension strip 3 secured in lasted position by 15 tacks 20 driven into the insole. The tacks 20 which are driven to secure the upper to the insole at the shank and forepart pass through the upper flap 8 of the insole and are clenched against the plate 13, and the tacks 20 securing the heel and extreme toe portions of the upper are clenched by the plate 13 on the inner surface of the insole. The succeeding operations upon the shoe including the attachment of an outsole to the welt 6 are performed in the customary manner.

After the last 12 is withdrawn from the shoe, the lower flap or slip sole 9 is cemented to the upper flap 8, thus covering the lasting tacks 20 in the shank and forepart of the shoe. A heel seat filler is preferably located in the shoe at the heel to cover up the heel nails and thus form a continuous smooth surface on the interior of the shoe upon which the foot of the wearer 35 bears.

It will be noted that the above described shoe can be manufactured at a greatly reduced cost due to the reduction in the amount of upper materials for the shoe and 40 the elimination of several skilled and costly operations, such for example as pulling-over lasting and inseaming, which are a part of the process of making the commercial shoe. Moreover, the shoe is flexible owing 45 to the manner in which the upper materials are secured to the welt and insole for the attachment of the outsole. It will be further noted that the strip 3 of canvas secured to the lower edge of the molded upper provides 50 for readily securing the upper to the insole without the usual waste of upper material and by securing the welt to the lower edge of the molded upper and to this canvas strip the inner seam is additionally reinforced 55 and the shoe prevented from stretching and losing its shape.

Having described my invention, I claim as new and desire to secure by Letters Patent of the United States:—

- 60 1. That improvement in the art of making shoes which consists in molding to its final shape the toe end of a shoe upper which has been cut substantially to its final outlines, permanently securing to said upper along 65 the lower margin thereof, an extension strip

for lasting, providing an insole having upper and lower flaps, assembling said upper and said insole upon a last, lasting the upper over the insole and clenching the lasting fastenings between the insole flaps 70 nearly to the toe end and upon the inner face of the insole at the toe and heel ends and then attaching an outsole.

2. That improvement in the art of making shoes which consists in molding substantially to their final shapes, the heel and toe ends of a shoe upper which has been cut substantially to its final outlines, permanently securing to said upper along its lower edge an extension strip for lasting, 75 and a welt strip, providing an insole having upper and lower flaps, assembling said upper and said insole upon a last, lasting the upper over the insole and clenching the lasting fastenings between the insole flaps 80 in the shank and the forepart and upon the inner face of the insole at the toe and heel ends, and attaching an outsole to said welt.

3. That improvement in the art of making 90 shoes which consists in providing an insole having upper and lower flaps, assembling upon a last said insole and an upper having its toe and heel ends molded to shape, lasting the unmolded portions of the upper over 95 the insole and securing both the molded and unmolded portions of the upper to the insole by lasting fastenings driven through these parts and having their points clenched between the insole flaps at the shank and 100 forepart and upon the inner face of the insole at the toe and heel ends and securing an outsole to said upper and insole.

4. That improvement in the art of making 105 shoes which consists in molding the toe and heel ends of an upper to the final shape of a lasted shoe, securing a lasting strip to the lower edge of said upper in such manner that said strip extends beyond said edge, securing a welt strip to the lower edge of the 110 upper, providing an insole having upper and lower flaps, assembling said insole and upper upon a last, lasting said upper over the insole and clenching the lasting fastenings between the flaps in the shank and forepart and upon the inner face of the insole 115 at the heel and toe ends and securing an outsole to said welt.

5. That improvement in the art of making 120 shoes which consists in molding to its final shape the toe end of a shoe upper which has been cut substantially to its final outlines, permanently securing a lasting strip to the lower edge of said upper so that it extends beyond the edge thereof, securing a welt 125 strip to the lower edge of said upper; providing an insole having upper and lower flaps, one of said flaps extending over the shank and forepart of said insole, assembling said upper and said insole upon a 130

last, locating a clenching plate between the flaps of said insole, lasting the upper over the insole and clenching the lasting fastenings upon said plate, and securing an out-
5 sole to said welt.

6. That improvement in the art of making shoes which consists in cutting an upper substantially to the size which it is to have in the finished shoe, molding the upper at
10 one or more points to give it the form of a lasted upper, securing a lasting strip to the lower edge of said upper so that it projects beyond the edge thereof, assembling an insole and said upper upon a last, lasting said
15 upper over the insole with the aid of said strip, securing the upper through said strip to the insole and attaching an outsole to said upper.

7. That improvement in the art of making
20 shoes which consists in molding to its final shape the toe and heel ends of a shoe upper which is cut to such a size that its lower edge terminates substantially at the last edge, permanently securing to the lower
25 edge of said upper an extension strip for lasting and a welt strip, providing an insole, assembling said upper and said insole upon a last, lasting said upper over said insole, securing the upper by said strip to the
30 insole and attaching an outsole to said welt.

8. That improvement in the art of making

shoes which consists in cutting a shoe upper substantially to its final outline, permanently securing to the upper along its lower marginal edge a lasting strip which extends be-
35 yond the lower edge of the upper, securing a welt strip to the lower marginal edge of the upper along its inner edge, assembling the upper upon a last together with an insole, lasting the upper and securing it in
40 lasted position to the insole by the lasting strip, and attaching an outsole to the welt.

9. That improvement in the art of making shoes which consists in cutting a shoe upper substantially to its final outline, molding
45 the toe end of the upper to the shape desired in the finished shoe, permanently securing to the lower marginal edge of the upper a lasting strip which extends beyond the outer edge of the upper and a welt strip, provid-
50 ing an insole, assembling the upper and the insole upon a last, lasting the upper and se-
curing it in lasted position to the insole by the lasting strip, and attaching an outsole
55 to the welt.

In testimony whereof I have signed my name to this specification in the presence of two subscribing witnesses.

KARL ENGEL.
